(57) CLAIM

The ornamental design for a transaction card packet, as shown and described.

DESCRIPTION

FIG. 1 is a front perspective view of a transaction card packet according to an embodiment of the invention;

FIG. 2 is a top plan view of the transaction card packet of FIG. 1;

FIG. 3 is a front elevation view of the transaction card packet of FIG. 1;

FIG. 4 is a right elevation view of the transaction card packet of FIG. 1, the left elevation view being a mirror image thereof;

FIG. 5 is rear elevation view of the transaction card packet of FIG. 1; and,

FIG. 6 is a bottom plan view of the transaction card packet of FIG. 1.

The broken lines in FIGS. 1, 3 and 5 illustrate environmental subject matter and form no part of the claimed design.
